T. V. *James Doherty* A. M.

UNITED STATES PATENT OFFICE.

JAMES DOHERTY, OF CHICAGO, ILLINOIS.

STEAM AND AIR INJECTOR.

Application filed April 24, 1923. Serial No. 634,232.

The present invention relates to boiler and furnace construction, and has particularly to do with means for increasing the combustibility of fuel.

- 5 Reference will be had at various times to my Patent 1,402,843, issued January 10, 1922, and one of the objects of this invention is to provide a modification of and improvement upon the construction therein described.
- 10 Another object of the invention is to provide in a single furnace an adaptability whereby coals of different types may be burned with equal efficacy, the invention providing means for securing complete and regulated combustion of such fuel.

15 Another object of the invention is to provide means for introducing air and steam at various points within the combustion chamber and flue passages of a furnace or boiler in order to promote complete oxidation of the fuel material and fuel gases. It is contemplated that such steam and air will be admitted to the fire box and flue passages in regulated portions, and that the steam will be injected transversely of the gas travel in the boiler or furnace, and that the air will have a controlled temperature.

20 The invention comprises, in part, the manner of introducing and heating air to be supplied to the combustion chamber, in part, to the manner in which steam is introduced therein, and in part, to the arrangement of the air and steam passages and of the steam supply means within the furnace structure.

25 These objects, and such other objects as will hereinafter appear, are attained by the construction, combination and arrangement of parts now to be described.

30 The accompanying drawings illustrate the preferred form of the invention, and it will be manifest from the description herein that the construction and arrangement thereof may be varied without departing from the invention.

35 In the drawings:

Fig. 1 is a perspective view of a typical sectional, water-heating furnace with the side wall broken out and the interior parts shown in vertical and oblique sections;

40 Fig. 2 is a transverse section adjacent the front water curtain therein;

Fig. 3 and Fig. 4 are details of the steam pipe construction, and

45 Fig. 5 is a plan view of one of the sections of the air duct forming members.

Like reference characters are used to design-

nate similar parts in the drawing and in the description of the invention which follows.

The furnace shown in the drawing is generally of the same type as that illustrated in my patent referred to above, and comprises front and back water-containing sections 1 and 2, and a plurality of intermediate water-containing sections, 3, 4, 5, 5^a and 6, all of which sections have the same general external configuration and are adapted to be clamped or otherwise secured to one another, as is usual in sectional boilers. The water spaces of each intermediate section and those in the front and back sections 1 and 2 are in communication, as is also customary in boiler construction.

In assembled relation, the several sections referred to above provide the fire box and the flue spaces for exposing the requisite surfaces for the transfer of heat from the combustion gases to the water within the water spaces. To increase the surfaces exposed to the heated gases of combustion as well as to augment the water covered surfaces, sections 3 and 4 are substantially of a T-shape in cross section, the depending portion, or the stem of the T, being shorter in the latter sections. Said sections 3 and 4 form the roof or crown of the fire box which has its greatest vapor capacity immediately adjacent and in front of section 5 which comprises a cross member or baffle containing a water space and depending considerably below the crown wall of the fire box. Said section marks the rear limit of the upper part of the fire box and provides a water curtain intermediate the front and rear portions thereof.

In the rear of section 5 a number of sections 3 are consecutively arranged and have adjacent thereto one or more sections 6 in which the water spaces are separated one from another to provide flue spaces or passages through which the heated gases rise into the upper section of the furnace, while adjacent the rear section 2 and intermediate said section and section 6, section 5^a is placed.

After combustion gases pass through the flue spaces in section 6 and between said section and the adjacent sections 3 and 5^a, these gases are passed forwardly through horizontally directed side flues 7 and then rearwardly through a horizontal center flue 8 arranged parallel to flues 7 to the take-off and chimney, which latter are not illustrated. The flue arrangement described is not new and is not essential to the success of the invention about to

be disclosed for other flue arrangements may be employed without decreasing the efficacy of the invention.

The bottom of the fire box comprises a perforate up draft grate 9 and is ordinarily arranged in parallel relation to the crown wall and hence is substantially horizontal. Its rear end terminates with and abuts upon the vertical portion or a bridge wall or bank 10 which is upwardly inclined as it approaches the lowermost and depending section of section of section 5^a at the rear of the furnace.

Coal is supplied in the usual manner through a feed door in the front section 1 and air is admitted to and beneath the fuel bed upon the grate 9 by an ash pit door also disposed in said section 1 and at the bottom thereof. The air admitted through said ash pit door, of course, constitutes the major portion of air employed in obtaining combustion of the fuel in the fire box.

I have designated the water curtain of section 5 by the ordinal 11. The lower edge thereof extends transversely and horizontally over the rear part of the grate 9 and fuel bed, occupying a level which is somewhat nearer to the grate than to the crown wall, and in this position, as in Patent 1,402,843, it cooperates with the fuel bed directly below it, to form therewith a somewhat restricted passageway or throat through which the fire box opens into the flue space at its rear. Substantially the entire volume of fire gases developed in the furnace flows through this passageway which extends across the furnace with practically uniform vertical dimension. As in the patent referred to above, a duct substantially coextensive with the water curtain 11 is provided, said duct being designated by the ordinal 12, and is substantially coincident with the lower edge of said water curtain. Atmospheric air is admitted to said duct through appropriate damper-controlled inlet openings 13 in the side legs of section 5, as shown in Fig. 2, and such air is discharged from and distributed through a plurality of uniformly spaced and downwardly directed exit orifices 14 opening upon the lower side of duct 12, and therefore, in the direction of the fuel bed. Such air flows into and through said duct and its orifices because of the chimney suction which suffices to produce a vigorous discharge through the row of orifices and because the air path through the grate 9 is more or less obstructed by the fuel thereon. The velocity is so great as to cause the air to penetrate the throat passage above referred to and seemingly to impinge against the subjacent bed of fuel, creating an extraordinary mixing effect and turbulence in the fire gases at that passage which is manifested in practical operation by a sheet of livid white flame extending directly from the water curtain 11 to and through the horizontal flues of the furnace.

In the patent heretofore granted to me I have fully discussed the effect of the water curtain 11 upon the atmospheric air as it enters the furnace; and reference can be had thereto for the purpose of fully understanding the effect of both proper and improper temperatures and proper and improper velocities for the air so admitted.

It is reiterated that the position of section 5 herein shown is a proper position for the admission of supplemental air to the fire box, and to this it may be added, that the employment of water sections of less vertical dimensions, as indicated by the use of sections 4, immediately in front of the water curtain 11 contained in section 5, increases the gas space adjacent said section and materially assists in the securing of a whirling of the generated fuel gases, causing most intimate mixture thereof and of the supplemental air admitted by duct 12, whereby substantially complete combustion of such gases is obtained.

The general construction of section 5 has not been modified over that disclosed in my earlier patent. The upper and front portion of water curtain 11 is completely protected by a vertical tile fire-wall 15 contiguous to the water curtain 11 at its front, and said wall is maintained in position by resting upon the exterior upper surface of duct 12 and by contact between a portion of its upper section and the enlarged portion of the side legs of the furnace adjacent the crown wall.

The atmospheric air as it is admitted to the combustion chamber through the duct 12, passes between a series of teeth 16 formed along the lower edge of the water curtain 11 and providing therebetween the exit orifices 14, said teeth being of substantially equal size and all containing water from the water curtain 11. The duct 12 is completed by resting upon teeth 16 two L-shaped members 12' which may be described as abutting channel bars having a rib 17 of increasing width as the side of the section 5 is approached. The spaces 14 intermediate the teeth 16 are substantially of the same width as the teeth themselves but their other dimension is graduated by rib 17 so that while air is delivered to the fire box in closely adjacent and uniformly spaced jets or blasts, such jets are of greater cross section as (in one dimension) the center of the fire box is approached. Such an arrangement insures admission of air in equal volume through each orifice 14 and tends to prevent localization of the air supply at the orifices adjacent the section side walls. The direction of the air movement as it is jetted into the fire box is mainly downwardly and slightly forwardly, and a turbulence is obtained with the combustion gases because the velocity of the air as it enters the combustion chamber is such as to disturb the general direction and movement of the combustion vapors. The wall 15, being struc-

turally separate from section 5, is entirely free to expand and retract under thermal changes which occur in the combustion chamber of the furnace without injury to itself and without imparting strain to or upon the metal of the water curtain proper or to the walls of section 5.

It is well established, and equally well evidenced by a number of patents which have been granted, that the admission of steam, if it is properly regulated, to a fire box in order that it may come into contact with the combustion gases, has a salutary effect upon combustion, rendering it more complete and increasing the volume of heat units obtained. So far as I have been advised, none of the devices which heretofore have been presented, has caused the proper comingling of the steam with the combustion gases, and therefore the devices have been failures or partial successes. It is also aptly demonstrated that the admission to the fire box and flues of supplemental air, in regulated quantities, and with proper conditions of ingress, tends to increase the combustibility of fuel material, and permits of complete oxidation of the carbon thereof within the walls of the furnace, doing away with the loss of heat resultant from partly consumed fuel vapors or gases, and overcoming smoke nuisances. I will now describe my improved methods of admitting steam and air, to a furnace whereby to cause proper comingling thereof with the combustion gases thereof. Such description will also include the means which I have employed whereby such air and steam may be admitted at various stages of fuel combustion with the combustion gases and cause their complete oxidation and maximum heat development.

I have found, from actual practice, that in certain classes of fuel, air which is admitted through the updraft grate 9 and through duct 12 in section 5 in which is formed the water curtain 11, is insufficient to provide complete combustion of the fuel, and the gases generated by such fuel, and such gases reach the flue spaces rich in uncombined carbon and other combustible products which may be made to ignite and produce additional heat, if additional air is admitted at the proper point in the combustion space. To overcome this condition, immediately adjacent the rear section 2 and intermediate said section and section 6 through which flue spaces are arranged, a section 5', identical with section 5, is provided. Air there admitted is adapted to be thrown vertically downward and slightly forward against the inclined top of wall 10 in order that it may quickly mix with the onrushing current of heated gases endeavoring to reach the horizontal flues 7 and 8 above.

It will be noted that gases which pass under the water curtain 11 will attain a high

momentum because of chimney suction. But the rearwardly disposed section 5' is nearer to the source of the chimney suction and naturally will be more strongly affected thereby than gases which have to pass beneath the water curtain 11 and through the restricted throat thereunder. This being true, atmospheric air admitted through section 5' will have considerable velocity, enough to cause it to impinge and agitate and rapidly come into contact with the heated combustion gases. Such portions of the combustion gases as have had insufficient intermixture of oxygen to be completely consumed in the fire box and flue space adjacent thereto will take fire adjacent the rear flue space 6 and in the horizontal upper flues, thus increasing the heat values to be transferred to the water in the spaces about these flues. It is, of course, contemplated that the openings into ducts 12 and 12' will be damper controlled.

To convey a volume of steam to the combustion chamber and flue spaces in order that the steam may be decomposed into oxygen and hydrogen or otherwise aid combustion and increase the value of the burning fuel, I provide a pipe 20 which is bent to pass from the top of one of the furnace sections, preferably that of section 5, downwardly and horizontally through duct 12. A plurality of vents or openings are arranged upon said pipe, coextensive with the duct 12, in order that steam may escape therefrom in a finely atomized condition. The openings of said vent are preferably in a single row and downwardly pointed and may be so disposed as to coincide with the exit orifices 14. A valve (not shown) may be placed at any convenient point upon said pipe 20.

Said pipe 20 is continued out of and beyond duct 12 and passes horizontally under the updraft grate 9, where a plurality of openings or vents similar to those described above are arranged in the top surface of the pipe. A second valve (not shown) may be provided upon pipe 20 at any convenient point intermediate its two horizontal sections.

In the arrangement thus described, steam is finely divided or atomized before passing into the combustion chamber. That which is released in the duct 12 passes therefrom in intimate mixture with the air admitted through said duct and impinges the burning combustion vapors from above while moving in a vertical downward direction forming what may be aptly termed a curtain of vapor across the restricted throat passage beneath water curtain 11. The steam so discharged into the combustion chamber has equal or greater velocity than the air with which it is mixed, and immediately comes into contact with the combustion vapors, creating great turbulence therein, and producing immediate changes therein which increase the combustibility of the gas mixture.

Steam vapor discharged vertically upward through the updraft grate 9, in passing therethrough and entering the combustion chamber, behaves in the same manner as the steam 5 which is admitted into the duct 12. It too is mingled with air. This may become part of the curtain of vapor previously adverted to. The perpendicular flow of steam vapor from above and from below the fuel bed differs from the steam flow produced by other 10 devices, so far as I am informed, in that none of these other devices secures proper and intimate admixture of the steam vapor and the combustion gases, and none provides means 15 for creating a steam or vapor curtain through which the combustion gases must necessarily pass on their journey to the flue passages.

In the rearwardly disposed section 5^a, I have also provided means for atomizing 20 steam vapor, and allowing it to come into contact with the air admitted through said section, for the pipe 21 passing into duct 12^a in section 5^a is connected with pipe 20 to receive steam therefrom. If required, a valve may 25 also be placed upon pipe 21 at any convenient point.

An additional supply of steam may be employed, without admixing such steam and air, through the agency of pipe 22, valve controlled but valve not shown, which pipe is disposed immediately adjacent to and rearward of the rearmost of sections 3 above the fuel bed. The vents or openings for the discharge of steam therefrom are, preferably 30 disposed upon the under side thereof in order that the steam discharged therefrom will be driven downwardly into the vapors being generated upon the grate 9 and increase the whirling movement of said vapors between 35 the fire bed and crown wall. Each of said pipes, 20, 21 and 22, may be provided with means whereby to cut off the flow of steam adapted to be discharged therefrom, just as each of sections 5 has a damper for the control 40 of the admission of air thereto.

A fire is begun in the usual way in my furnace. The portion of the fuel adjacent to section 1 takes fire first. That portion adjacent section 5 cokes more rapidly because the 45 gases therefrom come into contact with the air and the steam admitted from section 5 and pipes 20 and 22. The gases pass under the water curtain 11 and into the combustion space at the rear of the boiler where additional steam and air may be admitted through the rearwardly disposed sections 5^a and the pipe 21. Regulation of the flow of steam in the pipes 50 20, 21 and 22, and the admission of air through duct 12, may be modified as required and guidance may be had through observation of combustion conditions within the fuel chamber and of the smoke discharged from the chimney. Instead of the yellowish-white and sooty flame which is ordinarily 55 present in most boilers and particularly so

with certain kinds of fuel, there should be developed rapidly an incandescent flame indicative of admixture with the fuel gases of a sufficient supply of oxygen. Tests show greatly increased heat, both in volume and in 60 temperature. The effect produced is not unlike that of the "Bunsen" burner where air and gas may be mixed in order to completely consume the carbon particles within the gas, doing away with unconsumed particles producing both illumination and carbon deposits. The additional portions of air, together with the steam admitted to my furnace, properly regulated, adequately supply, at all times, a 65 sufficiency of combustion supporting elements.

As the combustion of fuel progresses, the fire works toward the front of the furnace and fully consumes the fuel, leaving only a finely disintegrated, completely exhausted 70 ash.

The arrangement of the several sections of the boiler may be varied at will, and I do not want to be limited to either the particular construction or the particular arrangement 75 herein shown, for the essence of the invention is not any particular and specific construction of the boiler, itself, but is the arrangement of air ducts in proper positions to insure more complete combustion, and in the 80 manner of admitting steam to the boiler to obtain a proper admixture and comingling of such steam with the combustible elements of the fuel gases. Of course, with respect to the employment of supplemental air, I have 85 provided the same general means for insuring admission of such air, and for obtaining its admission at a proper temperature, as I provided in my prior patent, hereinbefore frequently referred to.

It is quite manifest from the description which is given here that the water curtain and other features of section 5^a could with equal facility be made a part of rear end section 2 without departing from the spirit of 90 invention or modifying the efficiency of the device.

What I claim as new and desire to secure by Letters Patent of the United States, is:

1. An air and steam injector for use in a 95 furnace or the like, comprising an air duct provided with air passages of graduated and increasing size as the center of the furnace is approached whereby an equal volume of air is distributed from each of said passages and transversely of the direction of flow of combustion vapors in said furnace, and a steam supplying member provided with a series of equidistantly disposed orifices adapted to discharge equal volumes of steam into each 100 of said air passages.

2. A furnace having a fire box, a grate, a water curtain, and a bridge wall adapted to form a transverse restricted passageway into the rear portion of the fire box and between 105

said water curtain and said grate, in combination with a member for admitting steam transversely of said fire box, and means for admitting air to said furnace from the side thereof and for distributing such admitted air thereacross to form a curtain of uniformly mixed steam and air.

3. The combination as defined in claim 2 and in which said means for admitting air comprises a transverse air passage associated with the water curtain, the transverse air passage having graduated apertures therein, and in which said steam admitting member comprises an apertured pipe positioned in said transverse air passage and designed to discharge steam into said passage to become mixed with the air therein before the discharge thereof through the graduated apertures.

20 4. The combination with a furnace com-

prising a fire box, and flue, and a grate in said firebox and designed to support material in combustion, of a bridge wall against which burning material is designed to be banked, a water curtain depending from the roof of 25 said firebox and in advance of said bridge wall forming a restricted passageway across said firebox, means for discharging a mixture of air and steam from a sectional portion of said water curtain, and means for 30 discharging steam upwardly through said grate in a region directly beneath said water curtain whereby a mixed curtain of steam and air is produced across said restricted passageway.

5. The device described in claim 2, and having means for admitting steam below said restricted passage.

JAMES DOHERTY.
